United States Patent Office

Des. 189,489
Patented Dec. 27, 1960

189,489

VALET TRAY

Duane O. Jackson, Waterloo, Iowa, assignor to Distinguished Gift Manufacturers, Inc., Waterloo, Iowa, a corporation of Iowa

Filed Dec. 3, 1959, Ser. No. 58,537

Term of patent 14 years

(Cl. D44—10)

Fig. 1 is a perspective view of a valet tray, showing my new design,

Fig. 2 is an elevational view of one side,

Fig. 3 is an elevational view of the opposite side, and Fig. 4 is a bottom plan view thereof.

I claim:

The ornamental design for a valet tray, as shown.
